Eugene S. Dowdson

J. B. Virolet

UNITED STATES PATENT OFFICE.

JEAN B. VIROLET, OF NEW YORK, N. Y., ASSIGNOR TO JOHN W. HOYT, OF SAME PLACE.

DESIGN FOR FLOOR-CLOTHS.

Specification forming part of Design No. 1,171, dated November 29, 1859.

To all whom it may concern:

Be it known that I, JEAN BAPTISTE VIROLET, of the city, county, and State of New York, have invented or produced a new and original Pattern or Design for a Floor Oil-Cloth; and I do hereby declare that the following is a full and exact description of the same, reference being had to the accompanying photographic impression, serving as a drawing of the same.

The pattern or design is formed of two figures, which are made to alternate with and complete each other when the pattern is "dropped," or one figure placed opposite to the other, as will occur when the pattern is worked out in a floor oil-cloth, and is more

fully shown in the accompanying photographic impression.

What I claim as my invention or production, and desire to secure by Letters Patent, is—

The combination of figures and devices, herein described and represented in the accompanying photographic impression to form an ornamental pattern or design for a floor oil-cloth.

J. B. VIROLET.

Witnesses:
